UNITED STATES PATENT OFFICE.

ARTHUR B. MODINE, OF RACINE, WISCONSIN.

HEATING UNIT.

Application filed April 7, 1923. Serial No. 630,617.

My invention belongs to that general class of devices known as heating apparatus, and relates particularly to a heating unit adapted to be used in shops, factories, garages, storage warehouses and such other places as the same may be applicable.

The invention has among its objects the production of a device of the kind described that is simple, compact, convenient, of light weight, durable, efficient and satisfactory, and which may be installed at any desired point. More particularly it has as an object the production of an efficient, inexpensive and light weight unit, which may be attached to a wall or suspended or mounted on a suitable base, and which will have great capacity. It also has among its further objects the production of a device in which a circulator is employed which may be motor driven and in which the motor is entirely out of the current of heated air, whereby the same will not overheat even though not enclosed, and, as a matter of fact, which will, if anything, be maintained cool.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a front elevation of my improved form of device;

Fig. 2 is an enlarged sectional view illustrating the details of construction;

Fig. 3 is a sectional view taken substantially on the line 3—3 of Fig. 1;

Fig. 4 is a side elevation of the same with a portion broken away;

Fig. 5 is a sectional view taken substantially on the line 5—5 of Fig. 3;

Fig. 6 is a partial sectional view and side elevation illustrating a slightly modified form of device;

Fig. 7 is a front elevation of the same;

Fig. 8 is a partial sectional view illustrating another modified form of device; and

Fig. 9 is a front elevation of the device shown in Fig. 8.

In the drawings, wherein I have illustrated the preferred embodiment of my in-

vention, there is shown a heating unit of any suitable size and shape and preferably formed of any number of similar heating elements 1, secured together at their adjacent ends. Each of the heating elements comprises a pipe or tube, preferably having T-shaped ends, and radially extending from and secured to the elements 1 are fins 2 for radiating the heat from the pipes. The adjacent fins are spaced apart to provide air spaces therebetween through which the external air may pass and become heated by the heating medium passing through the unit.

At some suitable point the unit is provided with an inlet 3 for the heating medium and at another point it is provided with an outlet 4 for the condensation products from the heating medium. Bars 5 are inserted through the adjacent ends of the heating elements 1 for securing them together. The entire unit may be attached to a wall or suspended or mounted on a suitable base, in the present instance hanger rods 6 are secured at one end to said unit and at the other end to a suitable support. Extending about the perimeter of the unit is a casing 7, the same extending to one side thereof and tapering so as to decrease in area toward its free end.

In order to increase the heating capacity of the unit a circulator may be used, as for instance a fan 8 spaced from the unit and arranged at the discharge end of the casing 7 and driven by a motor or the like 9, arranged at the opposite side of the unit, said motor and fan having a shaft 10 drivingly connecting them.

In order to provide a suitable bearing for the shaft and a support for the motor, one of the heating elements, as for instance, the central member 11 is formed without the tubular portion connecting its sides, but carries brackets 12 and 13 integral therewith and extending in opposite directions, one of said brackets 12 providing a support for the motor 9 and the other bracket 13 having an aperture 14 therethrough forming a bearing for the shaft 10. An additional bearing 15 in line with the bearing 14 may be provided on the bracket 12 adjacent the motor support, if so desired.

A similar construction is shown in Figs. 6 and 7 in which case, however, I have shown the heating unit as consisting of substantially two assembled units or elements, which may be similar to the well-known type

2 of automobile or like radiator. This type of unit generally is very efficient and of light weight.

Referring to the figures, 20 represents a suitable base plate, in the particular device shown a channel, provided with the side flanges 21. Plate 20 carries a bracket 22 suitably secured thereto and having a part 23 projecting through the plate and carrying a bearing for the fan shaft.

10 I have shown a motor 24 having a fan shaft 25 extending as shown and provided with the desired number of fan blades 26. Obviously any suitable fan and driving mechanism may be employed for the purpose. The heating units in this case are indicated by the characters 27, the same representing substantially any of the well-known types of automobile radiator constructions. These are secured at either side of the base plate and communicate with the tanks or chambered ends or receptacles 28 and 29, which may be connected by the side pieces 28'.

25 I have shown ports at the top and bottom for the admission and discharge of the heating medium, such as hot water, steam or the like. The upper port 31 is in a chambered part provided with connecting parts 30 communicating with the tank 28, while the lower port 33 is provided in a similar part having communicating ducts 32 connecting with the tank 29. A casing or shell 35 is so arranged about and enclosing the 30 discharge end of the heating unit that the air is drawn to and through the unit, heated and discharged through the outlet end 36. Obviously this unit operates substantially similar to that previously described.

40 With the arrangement shown, whereby the fan is on one side of the heating unit and the motor on the other side, it will be noted that the motor is entirely out of the current of heated air so that the same will not be overheated, even though it is not enclosed, but on the contrary it will be maintained cool because the suction of the fan 8 will cause the cool air to be drawn past the motor and heating elements and be discharged outwardly 45 of the casing.

50 In the form shown in Figs. 8 and 9 the device is similar to that previously described in Figs. 6 and 7, except that in this instance the motor and fan are arranged on the same 55 side of the heating unit, whereby the overall depth of the device is materially lessened and the danger of unauthorized tampering with the motor is obviated to a large degree. In this form the bracket 23' is adapted to 60 be held to the part 20 by any suitable means, as for instance by bolts 42. A shield 40 is arranged to surround the motor 24, and the part 20 is provided with apertures 41 therethrough, whereby the cool air is drawn there-through, 65 past the motor by the fan, thereby

cooling the motor and increasing its efficiency of operation.

Having thus described my invention it is obvious that various immaterial modifications may be made in the same without departing from the spirit of my invention; hence I do not wish to be understood as limiting myself to the exact form, arrangement, construction and combination of parts herein shown and described or uses mentioned.

70 What I claim as new and desire to secure by Letters Patent is:

1. In a device of the kind described and in combination, a heating unit formed of a series of adjoined heating elements, a fan on one side of said unit and a motor on the other side thereof, one of said elements having a motor support formed integral therewith.

2. In a device of the kind described and in combination, a heating unit formed of a series of adjoined heating elements, a fan on one side of said unit and a motor on the other side thereof, one of said elements having a motor support formed integral therewith and having apertures therethrough to 85 provide bearings for the fan shaft.

3. In a device of the kind described and in combination, a heating unit formed of a series of adjoined heating elements, a casing around said unit and extending therefrom, a fan in said casing, a motor on the opposite side of said unit and a shaft connecting said motor and fan, one of said heating elements having a bracket integrally formed thereon and extending on opposite 95 sides thereof to support said motor and provided with apertures to form bearings 100 for the fan shaft.

4. In a device of the class described and in combination, a plurality of heating elements, means for suspending said elements in a vertical plane from a ceiling or the like, a bracket supported between the upper and lower ends of the elements, a motor and shaft therefor supported upon the bracket in 105 a horizontal plane, and a fan at the outer end of said shaft.

5. In a device of the class described and in combination, a plurality of heating elements, means for suspending said elements 110 in a vertical plane from a ceiling or the like, a bracket supported between the upper and lower ends of the elements, a motor and shaft therefor supported upon the bracket in a horizontal plane, said motor 115 being positioned upon one side of the heating elements, a fan at the outer end of the shaft arranged on the other side of the elements, and a casing carried by the elements and tapering to a restricted outlet at the 120 outer end of the shaft with the fan arranged in said outlet.

In testimony whereof, I have hereunto signed my name.

ARTHUR B. MODINE.
